UNITED STATES PATENT OFFICE

EDWIN L. WIEGAND, OF PITTSBURGH, PENNSYLVANIA

METHOD OF PRODUCING ELECTRICAL HEATING ELEMENTS

Application filed August 23, 1928. Serial No. 301,514.

This invention relates to a method of producing electrical heating elements of the type wherein the resistor is imbedded in a compact mass of granular refractory insulating material. The insulating material is desirably of high heat conducting quality and it may be contained in a receptacle or sheath of relatively thin sheet metal. Elements of this description are highly efficient, with 10 stand a very considerable amount of physical abuse, and are practically indestructible from overheating and long continued service.

It will be apparent from the following disclosure that electrical heating elements of various sizes and shapes may be produced by my present method, but for the purpose of illustration I have selected a cylindrical element like that employed in a percolator 20 unit disclosed in my copending application Serial No. 289,819, filed July 2, 1928, which has issued as Patent 1,778,926.

The purpose of the instant invention is to provide a simple and convenient method by 25 which electrical heating elements of the type aforesaid and of very high quality may be expeditiously and cheaply manufactured, and the method, in its more complete aspect, may be defined briefly as consisting in mounting 30 or suitably combining a resistor on or with a self-sustaining friable or collapsible core or support of granular refractory electrical insulating material, and then applying thereto or encasing the same in a quantity 35 of similar mobile material and compacting or compressing the assembly (preferably in a sheet metal sheath) so that the support or core is crumbled or collapsed and merged with the mobile material so that the whole 40 becomes a relatively dense or homogeneous mass with the resistor embedded therein.

One manner of performing the method is shown in the accompanying drawings where- 45 in Fig. 1 is a side elevation of the friable or collapsible core or support with the resistor applied thereto; Fig. 2 is a central vertical section through a sheet metal receptacle that constitutes the sheath of the completed ele- 50 ment; Fig. 3 is a central vertical section through an apparatus used in producing the

element and showing the parts of the element contained therein before compression; Fig. 4 is a similar view showing the contents of the receptacle compacted by means of a plunger that forms a part of the apparatus; 55 Fig. 5 is a central vertical section through the completed element; and Fig. 6 is a sectional plan on the line 6—6 of Fig. 5.

In the present example of the method, a receptacle 1, which is preferably of relatively thin sheet metal of suitable quality, and which constitutes the sheath of the heating element, is placed within a cylindrical cavity of a retainer 2 to the upper end of which is applied an annulus 3 having a bore 60 that is approximately of the same diameter as the internal diameter of the receptacle 1. In the receptacle 1 is placed a friable or collapsible core or support 5 (that carries the resistor as will hereinafter be explained) 70 that is desirably formed of granular refractory electrical insulating material. In its present form it is shown as having an external spiral groove 6 that communicates, through a notch 7, with a longitudinal passageway 8, the opposite end of the spiral groove 6 opening into a recess 9 in the top of the support or core. 75

The resistor, designated 10, consists of a metal wire or filament that may or may not 80 be wound into a helix of very small diameter, in a manner well known to those familiar with the subject, and it is applied to the core or support 5 before the latter is deposited in the receptacle 1. In applying the resistor 10 to 85 the core or support 5, it is wound about the exterior of the core or support within the groove 6 and one of its ends is offset inwardly into the notch 9 and thence turned axially of the core or support, while its opposite end is turned downwardly through the notch 7 that is formed in the periphery of the enlarged lower end or base 11 of the core or support and then inwardly and upwardly through the 90 passageway 8 in substantially parallel relation to the opposite end portion of the resistor.

A quantity of mobile granular refractory electrical insulating material is next poured 100 into the receptacle 1, filling the same and (de-

pending upon the capacity of the receptacle and the compressibility of the material) a part of the loose mobile material may accumulate within the bore of the annulus 3.

5. A plunger 12, of a diameter substantially equal to that of the bore of the annulus 3, and having ducts 13 for the accommodation of the end portions of the resistor 10, is inserted within said bore and is forced downwardly to 10 compress the insulating material within the receptacle 1 and collapse or crumble the friable core or support 5 so that its identity becomes lost and it is merged with the insulating material that was previously mobile, the 15 whole becoming a dense, homogeneous mass within which the resistor 10 is embedded.

- The annulus 3 is then removed and the receptacle 1 is withdrawn from the retainer 2, after which a metallic disk or closure 15, with 20 a disk 16 of mica or other suitable insulating material, is placed within the open end of the receptacle in contact with the insulating material and the rim of the receptacle is then peened inwardly to hold the disks in place. 25 It will be noted that the metallic disk 15 has relatively large apertures and that the disk 16 of insulating material has relatively small apertures that register with those of the metallic disk, for the passage of the end portions 30 or terminals of the resistor 10.

The mobile insulating material, as well as that whereof the support or core 5 is made, may be the same as, or similar to, that described in my prior Patent No. 1614330, dated

35 January 11, 1927.

Having thus described by invention, what I claim is:

1. The method of producing an electrical heating element which consists in combining 40 a resistor with a self-sustaining collapsible support of insulating material, applying to said support a quantity of mobile insulating material, and compacting the assembly so as to collapse the support and integrate it and 45 the mobile insulating material with the resistor embedded in the resultant mass.

2. The method of producing an electrical heating element which consists in applying a resistor to a friable core of insulating material, surrounding said core with a quantity of mobile insulating material, and compacting the assembly so as to collapse the core and integrate it and the mobile insulating material with the resistor embedded in the 55 resultant mass.

3. The method of producing an electrical heating element which consists in combining a resistor with a self-sustaining collapsible support of insulating material, placing said support and the resistor in a receptacle, introducing mobile insulating material into the receptacle, and compacting the contents of the receptacle so as to collapse the support and integrate it and the mobile insulating material

with the resistor embedded in the resultant mass.

4. The method of producing an electrical heating element which consists in combining a resistor with a self-sustaining collapsible support of insulating material, placing said support and the resistor in a receptacle, introducing mobile insulating material into the receptacle, compacting the contents of the receptacle so as to collapse the support and integrate it and the mobile insulating material with the resistor embedded in the resultant mass, and applying a closure to the receptacle. 70

5. The method of producing an electrical heating element which consists in placing within an open sheath a self-sustaining collapsible support of insulating material carrying a resistor, introducing into the sheath a quantity of mobile insulating material, and compacting the contents of the sheath so as to collapse the support and integrate it and the mobile insulating material with the resistor embedded in the resultant mass. 80

6. The method of producing an electrical heating element which consists in placing within an open sheath a self-sustaining collapsible support of insulating material carrying a resistor, introducing into the sheath a quantity of mobile insulating material, compacting the contents of the sheath so as to collapse the support and integrate it and the mobile insulating material with the resistor embedded in the resultant mass, and closing the sheath. 90

7. The method of producing an electrical heating element which consists in winding a resistor on a friable core with the ends of the resistor projecting beyond one end of the core, placing the core and resistor in a metal receptacle with the opposite end of the core adjacent the bottom of the receptacle, introducing into the receptacle a quantity of mobile insulating material, and compacting the contents of the receptacle so as to crumble the core and integrate it and the mobile insulating material with the resistor embedded in the resultant mass. 105

8. The method of producing an electrical heating element which consists in winding a resistor on a core with the ends of the resistor projecting beyond one end of the core, placing the core and resistor in a metal receptacle with the opposite end of the core adjacent the bottom of the receptacle, introducing into the receptacle a quantity of mobile insulating material, compacting the same so as to effect a body of insulating material with the resistor embedded therein, and applying a closure to the receptacle. 115

9. The method of producing an electrical heating element which consists in applying a resistor to a core, placing the core and resistor in a metal receptacle, introducing into the receptacle a quantity of mobile insulating material, compacting the same so as to effect a 125

body of insulating material with the resistor embedded therein, placing a closure within the open end of the receptacle, and peening over the rim of the receptacle to hold said closure in place.

5 10. The method of producing an electrical heating element which consists in winding a resistor on a friable core with the ends of the resistor projecting beyond one end of the core, placing the core and resistor in a metal receptacle with the opposite end of the core adjacent the bottom of the receptacle, introducing into the receptacle a quantity of mobile insulating material, compacting the contents of the receptacle so as to crumble the core and integrate it and the mobile insulating material with the resistor embedded in the resultant mass, placing a closure within the open end of the receptacle, and peening over the rim of the receptacle to hold said closure in place.

10 15. The method of producing electrical heating elements of the character described which consists in winding a resistor on a self-sustaining friable resistor support, placing the resistor support with resistor thereon in a suitable casing, surrounding the same with a quantity of mobile insulating material, applying sufficient pressure axially of the support to collapse the support and integrate it with the insulating material so as to form a homogeneous mass with the resistor embedded therein and then closing the container.

20 25. The method of producing an electrical heating element which consists in supporting a resistor on a friable self-sustaining resistor support formed of insulation material, surrounding said resistor support and resistor with mobile insulation material and then applying sufficient pressure to the assembly and axially thereof to collapse the support and integrate it with the mobile insulation material so as to form a homogeneous mass with the resistor embedded therein.

30 35. In testimony whereof, I hereunto affix my signature.

EDWIN L. WIEGAND.
